FASTENING DEVICE

Charley T. Patterson, Springfield, Mo.

Application November 20, 1936, Serial No. 111,820

7 Claims. (CL. 229—35)

My invention relates to a fastening device for securing together sheet materials, such as box parts, braces, partitions and the like and particularly to a fastening device for use with parts formed of fibre board of the well known double faced corrugated type.

One of the objects of my device is to fasten such parts rigidly and securely against relative displacement in any direction.

10 Another object of my invention is to provide a means unitary with the wall parts for securing the parts together without the aid of mechanical means.

Another object of my device is to provide a 15 means for fastening such walls together without the use of staples, rivets, clips or the like.

A further object of my device is to provide a quick, easy means for uniting the walls by hand and without the tedious, slow work inherent in 20 other devices designed for such purposes.

A further object of my invention is to provide a fastening for wall parts and the like whereby the fastening operation is accomplished by a transverse bending movement of the fastening 25 elements instead of the usual endwise or edgewise insertion of one part within a slot or opening in the other part.

An additional object of my invention is to provide a device suitable for use with double faced 30 corrugated board or the like in which one of the elements is gripped flatwise between opposed edges of parts in the adjacent wall whereby the material of which the element is composed will be indented to form a groove in the face of the 35 element, the groove cooperating with the edges of the adjacent sheet or wall to securely unite the walls against relative movement.

A further purpose of my device is to provide a 40 means that may be formed in boxes or the like by the usual cutting-die processes employed for this purpose and in which the scoring may be accomplished at the same operation and on the same side of the material as the other usual scoring is made.

45 For accomplishing these objects I have provided a tongue member hingedly attached to one of the juxtaposed walls and in the other wall is provided an opening substantially co-registered with the tongue member and having a gate member lying within the opening and hingedly connected at one side thereof to the surrounding wall and lying co-planar therewith, the hinged portion of the tongue member being disposed transversely to the hinged portion of the gate member. Through this arrangement of parts the

tongue member may be bent through the opening in the opposed wall, causing the gate member to be bent to one side to allow the tongue member to pass and thereafter the gate member is returned to its original position to bind the tongue 5 between its edge and the adjacent edge of the wall. Throughout this specification and in the appended claims reference is made to the juxtaposed walls as "inner" and "outer" walls and it is expressly noted that the order of their relation 10 is reversible and that the tongue member and the gate member may be transposed if conditions warrant such a change, the designation "inner wall" and "outer wall" being in the main terms to 15 distinguish otherwise similar walls.

For a further description of my device reference is had to the accompanying drawing, in which:

Fig. 1 is a perspective view showing one embodiment of my device as applied to a box corner. 20

Fig. 2 is a plan view showing the tongue member of my device as embodied in Fig. 1.

Fig. 3 is a plan view of the gate member.

Fig. 4 shows the tongue member co-registered 25 over the gate member.

Fig. 5 is a fragmentary perspective view vertically sectioned on line a—b Fig. 4, showing how the parts are juxtaposed in operable relation.

Fig. 6 is a fragmentary perspective view showing the tongue member being passed through the 30 opening to displace the gate member.

Fig. 7 shows the tongue member bent sufficiently to allow the gate member to be returned to its original position.

Fig. 8 shows the gate member returned to its 35 position co-planar with the wall and binding the tongue member therebetween.

Figs. 9, 10 and 11 are plan views showing another embodiment of my device in which the tongue member has a widened portion outwardly 40 of its hinged portion, Fig. 9 showing the tongue member, Fig. 10 the gate member and Fig. 11 the tongue co-registered over the gate member.

Fig. 12 shows a perspective view of another embodiment of my invention in which a multiplicity 45 of tongue members and gate members are employed in one fastener.

Figs. 13, 14 and 15 are plan views showing the component parts used in Fig. 12, Fig. 13 showing the tongue members, Fig. 14 the gate members 50 and Fig. 15 indicating the manner of co-operative registration.

Fig. 16 is a perspective view of the embodiment disclosed in Fig. 12 and showing the tongue member being passed through the opening. 55

Fig. 17 is a perspective view of the rear of the device disclosed in Fig. 12 showing the tongue members gripped between the gate members and the wall.

5 Fig. 18 shows the device (in the embodiment disclosed in Figs. 9, 10 and 11) applied to a telescopic box cover and indicates the manner in which the tongue member may be folded against the inner face of the gate member to facilitate 10 telescoping over the box.

10 In the following detailed description similar numerals refer to similar parts throughout the several views.

15 In Fig. 1, 1 represents the outer wall in juxtaposed relation to the inner wall 2. The outer wall is provided with an opening defined by the wall edges 3, 4 and 5 and the appendant tongue member 6. This opening substantially overlies the gate portion 7. In Fig. 2 is shown the outer 20 wall 1 and the tongue member 6, surrounded by the wall edges 3, 4 and 5. 8 represents a scored line adjacent the juncture of the tongue 6 and the wall 1. In Fig. 3 is shown the inner wall 2 with the gate member 7 having a scored line 9 at 25 its juncture with the wall 2. Adjacent the scored line and substantially at right angles thereto is the wall edge 10 terminating in the wall edge 11 and completing the contour of the opening in which the gate lies is the wall edge 12.

30 In Fig. 4 is shown the outer wall 1 overlying the inner wall 2 with the tongue member overlying the gate member and registered in co-operative relation therewith. The scored lines are omitted in Fig. 4 for the purpose of clarity and the outline 35 of the gate member in the underlying wall 2 being indicated by the dotted lines 10, 11 and 12. The scored line carried by the tongue member substantially overlies the edge 10 of the gate member, and the scored line of the gate 7 substantially underlies the line 5 of the tongue.

40 Fig. 5, sectioned on line a—b Fig. 4 shows the juxtaposed walls 1 and 2 with the tongue member 6 registered with the gate member 7, and indicating the scored line 8 which facilitates bending 45 the tongue member and assists in reducing the thickness of the tongue member along the line at which it is gripped, inasmuch as the scored line affords a fulcrum which aids in embedding the wall edge 10 into the tongue 6.

50 Figs. 6, 7 and 8 show stages in the operation of fastening the device disclosed in Fig. 5. In Fig. 6 the tongue member 6 is being passed through the opening in the inner wall. In Fig. 7 the tongue member is bent far enough inward 55 to clear the gate member 7, while in Fig. 8 the gate member 7 is shown returned to its original position to bind the tongue member 6 between the gate member 7 and the wall edge 10.

60 In Fig. 9 is shown another embodiment of the tongue member 6 in which its sides and the abutting wall edges 3 and 5 are formed at an angle to produce a tongue wider as it recedes from the scored line 8, and a gate member designed to co-operate with such a tongue member 65 is shown in Fig. 10, the wall edge 11 being formed at an angle similar to that of the tongue member at 3, Fig. 9. These members are shown juxtaposed in Fig. 11.

70 In the modification of my device shown in Figs. 12 to 17 inclusive two tongue members 6 and 6a are arranged in opposed relation and which before folding have their outer edges meeting on a medial horizontal line 4 (Fig. 13). Also in this embodiment two gate members are arranged in opposed relation, 7 and 7a, and having their outer

edges meeting on a median vertical line 11 (Fig. 14). Fig. 15 indicates the manner of registration of these parts.

Fig. 16 a fastener of the dual type indicated in Fig. 12 is shown with one of the tongue members 5 6a bent inward to clear the gate members and showing the other tongue member 6 being started through the opening between the gate members. It will be noted that with this embodiment the additional width of the tongues outwardly of their 10 scored lines cause their outer edges to assume a curve longitudinally while passing through the opening while after clearing the inner wall they are permitted to straighten and after the gate members are returned to their original positions 15 the widened outer portion of the tongues afford additional locking means as shown in the rear view of such a device, Fig. 17. Similar conditions prevail with the embodiment shown in Figs. 9 to 11 inclusive insofar as the widened tongue 20 member is concerned, except that no impediment to the entrance of the tongue member exists on one side due to the fact that the side 11 of the opening in the inner wall 2 is formed at an angle which allows the tongue member to pass unob- 25 structed.

The tongue member of my device may be folded against the face of the inner wall after fastening or may be folded against the inner face of the gate member as indicated in Fig. 18 if for any 30 reason it is desired to do so to prevent obstruction.

When my device is applied to a folding object such as a box or the like the parts are located in the unfolded piece in such manner that upon 35 folding the piece the elements of the fastening device will be registered in the manner indicated herein while for separate pieces a similar registration is made between the parts prior to the fastening operation.

40 It will be noted that the operation of fastening is very simple. The tongue member is merely pushed sidewise (facewise) through the opening in the opposed wall, displacing the gate member which through its own resiliency has a 45 tendency to return to its original position after the tongue member is bent far enough inward to clear it. The gate member is forced into the opening to its original position where it securely locks the tongue member in place against either 50 transverse or radial movement. In this respect it will be noted that through forcing the tongue member against the edge 10 of the opening a groove is formed in the face of the tongue member resulting in a substantial hook or catch which 55 co-operates with the wall 2 to form a secure lock. This condition is especially evident when the device is applied to wall board of the double faced corrugated type or other relatively soft board.

My device requires no tools, eliminates staples, 60 brads, rivets, etc. and when completed the gate members close the opening tightly resulting in a continuous wall.

In the manufacture of objects embodying my device the incisions and scoring may be accomplished at the same operation and at the same time other necessary cutting and scoring is done and a further advantage will be apparent to those familiar with the manufacture of such devices in that it is unnecessary to remove any portion of 70 the material.

I claim:

1. A fastening device comprising adjacent juxtaposed walls, one of said walls having an opening therein, the other of said walls having a tongue 75

- member designed to swing transversely through said opening, a gate member within said opening for locking said tongue member in place in such transverse relation to said walls, said gate member having a hinged portion adjacent its juncture with the adjoining wall, said hinged portion being substantially in right angled relation to the plane of said tongue member when said tongue member is in said transverse position.
- 10 2. A fastening device for uniting sheet material, comprising hinged tongue means formed integral with one sheet, an adjacent sheet having an opening co-registered with said tongue means, and hingedly associated with said opening and lying therewithin, gate means designed to grip said tongue means between said gate means and the periphery of said opening adjacent the hinged portion, the hinged portions of said tongue means and said gate means being angularly disposed.
- 15 3. A fastening device for attaching two facially opposed sheets together, comprising a tongue integral with one sheet and having a bending line adjacent said sheet, and a gate integral with the other sheet and having a bending line adjacent said latter sheet, said gate being positioned to underlie the tongue and with its bending line transverse to the bending line of said tongue, said gate having adjacent its bending line an edge substantially underlying the bending line of said tongue, the gate carrying sheet having a wall edge substantially abutting the aforesaid edge of the gate whereby the tongue may be gripped therebetween.
- 20 4. A fastener for securing sheets of fibre board and the like together in face to face relation, comprising hinged tongue means formed integral with one sheet, and hinged gate means formed integral with and co-planar with an adjacent sheet and lying within an opening in said last named sheet, said tongue means and said gate means having their hinged portions angularly disposed, said gate means substantially underlying said tongue means whereby when said tongue means is depressed transversely of the face of the sheets and against the gate means the latter will be correspondingly deflected to allow the tongue means to pass through the opening and whereby upon returning the gate means to its original position the tongue means will be bound between said gate means and the periphery of the opening adjacent the hinged portion of said gate means.
- 25 5. A fastening device comprising an outer wall, an inner wall, said walls being disposed in face to face relation, said outer wall being incised to form a tongue integral therewith, said tongue being scored on the inner side to form a bending line near its juncture with said outer wall, said inner wall being incised to form a gate integral therewith, said gate being scored on the inner side to form a bending line near its juncture with said inner wall, said gate being disposed in underlying relation to said tongue and in such manner that their bending lines converge at an angle,
- 30 said gate having adjacent its bending line an edge substantially underlying the bending line of said tongue, said inner wall having an edge substantially coterminous with said edge of the gate, whereby when said tongue is pressed inwardly against said gate the latter will swing inwardly providing an opening in the inner wall through which the tongue may be swung to a position which will allow the gate to be returned to its original position to bind the tongue transversely between said gate and said inner wall.
- 35 6. A fastener for folding boxes and the like in which certain parts of the object overlap other parts in juxtaposed face to face relation, said fastener comprising an outer wall, said wall having a tongue member formed integral therewith, said tongue member lying in co-planar relation to said wall and having near its juncture with said wall a bendable portion for allowing said tongue to be bent inwardly out of the plane of said wall to a position transverse to the plane of said wall, said tongue member having a widened portion outwardly of its bendable portion, and an inner wall having an opening therein, said inner wall having a gate member formed integral therewith, said gate member lying in co-planar relation to said inner wall and within said opening, said gate member having near its juncture with said wall a bendable portion for allowing the gate member to be bent inwardly out of the plane of said inner wall to a position transverse to the plane of said inner wall, said gate member having adjacent one end of its bendable portion and angularly disposed therewith a straight edge, said edge being substantially co-extensive in length with the width of said tongue member at its bending portion, a portion of the inner wall substantially abutting said straight portion of the gate member and being substantially co-extensive in length therewith, a second wall portion adjacent said first named wall portion and disposed at an angle therewith, said tongue member and said opening being registerable in such co-operative relation that the bendable portion of the tongue member overlies the straight edge of the gate member and the abutting wall portion and in parallel relation thereto whereby the tongue member may be bent through the said opening and be bound between the parallel edges of the gate member and the abutting first named wall portion.
- 40 7. A fastening device for uniting sheet material, comprising a plurality of hinged tongue means formed integral with one sheet, an adjacent sheet having an opening co-registered with said tongue means, and hingedly associated with said opening and lying therewithin a plurality of gate means designed to grip said tongue means between said gate means and the periphery of said opening adjacent the hinged portion of said gate means, the hinged portion of said gate means and the hinged portion of said tongue means being disposed in angular relation.

CHARLEY T. PATTERSON.
